[57] CLAIM

The ornamental design for a combination photograph holder and display, substantially as shown and described.

DESCRIPTION

FIG. 1 is a perspective view of a photograph holder and display showing my new design;

FIG. 2 is a perspective view thereof in an open position;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view thereof, the opposite side being the same in appearance; and

FIG. 8 is a cross-sectional side elevational view, taken along line 8—8 of FIG. 5.
